HARRY L. BEACH, OF COSHOCOTON, OHIO

DISPLAY RACK

Application filed May 9, 1930. Serial No. 451,048.

This invention relates to display racks and, among other objects, aims to provide an improved collapsible metal rack for automobile tires and the like.

5 In the accompanying drawings:

Fig. 1 is a front elevation of a rack embodying the invention;

Fig. 2 is a sectional view taken on the line 2—2 of Fig. 1;

10 Fig. 3 is a sectional view taken on the line 3—3 of Fig. 1; and

Fig. 4 is a fragmentary side elevation showing a portion of a supporting leg and one of the rack carrying members.

15 In order to display automobile tires of different makes and sizes to the best advantage, it is desirable to support them on stepped racks or holders so that the upper portion of each tire is visible and the customer can

20 see its name. Heretofore, tires have usually been displayed on stepped wooden stands or placed, side by side, in show windows. These methods of display require a great deal more space than is necessary. This in-

25 vention, therefore, aims to provide an improved relatively simple and handy portable metal rack having provision to carry a number of tires in such manner that they can easily be inspected by customers.

30 Referring particularly to the drawings, the preferred design of rack is there shown as embodying a vertical frame having spaced uprights 10, conveniently composed of structural angles. The upright members

35 are connected at their lower ends by means of an angle bar 11 and at their upper ends by a cross bar 12 to the latter of which may be secured an ordinary display plate 13. The width of the frame is preferably

40 slightly less than the outside diameter of the tires to be supported, so that the frame is practically hidden by the tires.

A pair of rack-supporting leg members 14, also conveniently composed of structural angles, are here shown as being pivotally connected at their upper ends to the flanges of the uprights 10 by means of pivots 14a. These leg members are adapted to be swung inwardly like the legs of an easel against

50 the vertical frame so that the rack can be

collapsed and shipped in a relatively small carton or crate. The upper ends of the supporting legs are conveniently beveled, as shown in Fig. 2, so that the toe portions will act as stops against the rear flanges of the 55 uprights 10 when the legs are opened and inclined at an angle to the vertical, as shown. The lower ends of the supporting legs are shown as having a cross brace 15 correspond- 60 ing to bar 11.

To hold the legs extended, braces 16 in the form of flat metal bars may be bolted to the flanges of the uprights and of the supporting legs. The arrangement is such that one of the bolts 16a on each brace may be re- 65 moved and they may be swung against the rear flanges of the uprights when the rack is collapsed.

Connected at intervals to the supporting legs 14 are a series of cross bars 17 conveniently made of flat pieces of metal, each having end ears 18 bent at right angles and pivoted as at 18a to the side flanges of the legs. The width of the flat cross bars and the location of their pivots are such that 70 their upper edges contact with the front flanges of the legs 14 when they are swung to a vertical position or lie in vertical planes, as clearly shown in dotted lines in Fig. 4. 75

Thus the cross bars cannot swing counter- 80 clockwise, as viewed in Figs. 2 and 4, and may support a load. When the cross bars are in the full line position of Fig. 4 (see also the uppermost cross bar in Figs. 1 and 2), their outer edges are in contact with the outer flanges of legs 14, and hence cannot be swung clockwise. Thus the flanges of legs 14 limit swinging of the cross bars on their pivots 18a.

To each of the pivoted cross bars 17, a 90 U-shaped tire supporting member 19 is secured. In this instance, the tire supporting members are made of round bars having their ends screw-threaded and they are connected to the pivoted cross bars by means of nuts 20 on both sides of the bars, the arrangement being such that the nuts may be tightened against the opposite faces of the cross bars to hold the supporting members 95 rigid. Moreover, this connection enables 100

the supporting members to be adjusted so as to accommodate tires of different thicknesses.

5 The entire rack is conveniently supported on castors or rollers 21 which are secured to the cross braces 11 and 15 adjacent to their ends or near the corners of the bottom portion of the rack.

10 From the foregoing description, it will be seen that a series of tires may be supported side by side in vertical planes by the improved supporting members. The shape of the bars 19 which receive the tires between them and the cross bars 17 is such that the 15 lower portion of the tire cannot slip through them between their bent ends. Furthermore, the construction of the improved rack is such that it can be made very cheaply of standard structural parts. It is durable and 20 has no weak parts which are easily broken. Moreover, it can be collapsed and shipped in a relatively small crate or shipping space.

25 Obviously, the present invention is not restricted to the particular embodiment thereof herein shown and described.

What I claim is:

- 30 1. A tire display rack comprising, in combination, a frame having upright members; rack supporting legs pivotally connected at their upper ends to said upright members intermediate their ends; cross bars pivotally connected at intervals to said supporting legs; and U-shaped tire engaging rods adjustably secured to said cross bars.
- 35 2. A tire display rack comprising, in combination, an upright frame; a pair of inclined legs secured to the frame, said legs being made of angles each with one flange on the outside, said flanges extending toward each other, the other two flanges of the angles lying in vertical planes and inside of the first named flanges; a series of spaced cross bars each having end ears pivoted to the inside flanges and contacting along one longitudinal edge with the inside faces of the outside flanges; and a tire-supporting member secured at its opposite ends to each cross bar and spaced therefrom a sufficient distance to admit therebetween the lower 40 portion of a tire treadwise and lying in a substantially horizontal plane so as to support a tire in a substantially vertical position; the several tires so supported being spaced from each other so as to facilitate removal and replacement of the individual tires.
- 45 3. A tire display rack comprising, in combination, an upright frame; a pair of inclined legs secured to the frame, said legs being made of angles each with one flange on the outside, said flanges extending toward each other, the other two flanges of the angles lying in vertical planes and inside of the first named flanges; a series of spaced cross bars each having end ears pivoted to the inside flanges and contacting along one longitudinal edge with the inside faces of the outside flanges; and a tire-supporting member secured at its opposite ends to each cross bar and spaced therefrom a sufficient distance to admit therebetween the lower 50 portion of a tire treadwise and lying in a substantially horizontal plane so as to support a tire in a substantially vertical position; the several tires so supported being spaced from each other so as to facilitate removal and replacement of the individual tires.

In testimony, that I claim the foregoing as my own, I have hereto affixed my signature.

HARRY L. BEACH.
